US00D563333S

(12) **United States Design Patent** (10) **Patent No.:** **US D563,333 S**
Kim (45) **Date of Patent:** **** Mar. 4, 2008**

(54) **LIGHT EMITTING DIODE (LED)**

(75) Inventor: **Bang Hyun Kim**, Seoul (KR)

(73) Assignee: **Seoul Semiconductor Co., Ltd.**, Seoul (KR)

(**) Term: **14 Years**

(21) Appl. No.: **29/263,736**

(22) Filed: **Jul. 28, 2006**

(30) **Foreign Application Priority Data**

Apr. 5, 2006 (KR) 30-2006-0012564

(51) **LOC (8) Cl.** 13-03

(52) **U.S. Cl.** D13/180

(58) **Field of Classification Search** D13/180; D26/2; 257/79, 80, 81, 82, 88, 89, 95, 98, 257/99, 100, 678, 680, 433, 434; 313/483, 313/498, 500; 361/820; 362/555, 800

CLAIM

The ornamental design for light emitting diode (LED), as shown and described.

DESCRIPTION

FIG. 1 is a perspective view of a light emitting diode (LED) showing my new design;

FIG. 2 is a front elevational view thereof;

FIG. 3 is a left side elevational view thereof;

FIG. 4 is a top plan view thereof;

FIG. 5 is a bottom plan view thereof; and,

FIG. 6 is a sectional view taken along line 6—6 in FIG. 4.

1 Claim, 3 Drawing Sheets

FIG. 1

FIG. 2

FIG. 3

FIG. 4

FIG. 5

FIG. 6
